UNITED STATES PATENT OFFICE.

MAHKLON POLK BOWEN, OF LOS ANGELES, CALIFORNIA.

DESIGN FOR A CURTAIN-RING, &c.

SPECIFICATION forming part of Design No. 25,797, dated July 21, 1896.

Application filed January 31, 1896. Serial No. 577,618. Term of patent 14 years.

To all whom it may concern:

Be it known that I, MAHKLON POLK BOWEN, a citizen of the United States, residing at Los Angeles, in the county of Los Angeles and State of California, have invented a new and original Design for a Combined Curtain Ring and Clamp, of which the following is a specification.

This invention relates to a new and original design for a combined curtain ring and clamp, and it has for its object to provide a design of this character that shall be both useful and ornamental.

The leading feature of the design resides in a circular figure, and opposite sigmoidal-shaped arms tangentially joining diametrically opposite sides of said circular figure at their upper ends and provided at their lower adjacent ends with straight parallel extensions having inturned extremities and bounding therebetween a substantially U-shaped space.

In the drawings, Figure 1 is a perspective view of a combined curtain ring and clamp embodying the herein-described design. Fig. 2 is an elevation thereof.

Referring to the drawings, the numeral 1 designates a circular-shaped figure, and the numerals 2 2 designate opposite sigmoidal-shaped arms tangentially joining diametrically opposite sides of said circular-shaped figure at their upper ends, as at 3. The said sigmoidal-shaped arms are provided at their lower ends with parallel extensions 4, having inturned extremities 5, and bounding therebetween a substantially U-shaped space 6. The said opposite arms 2 combine with the lower side of the circular figure 1 to form a substantially crescent-shaped figure or space 7, which completes the design. 40

What I claim is—

The design for a combined curtain ring and clamp herein shown and described.

In testimony that I claim the foregoing as my own I have hereto affixed my signature in 45 the presence of two witnesses.

MAHKLON POLK BOWEN.
